DESIGN FOR A SECTIONAL CARGO CONVEYER

Henry B. Cohen, New York, N. Y., assignor to Sea
Emergency Devices, Inc., New York County,
N. Y., a corporation of New York

Application December 2, 1943, Serial No. 111,874

Term of patent 14 years

To all whom it may concern:

Be it known that I, Henry B. Cohen, a citizen
of the United States, residing in the city, county,
and State of New York, have invented a new,
original, and ornamental Design for a Sectional
Cargo Conveyer, of which the following is a spec-
ification, reference being had to the accompany-
ing drawing, forming a part thereof, in which:

Fig. 1 is a plan view of a sectional cargo con-
veyer showing my new design;

Fig. 2 is a side elevational view thereof; and
Fig. 3 is an end view thereof.

I claim:

The ornamental design for a sectional cargo
conveyer, as shown.

HENRY B. COHEN.
